UNITED STATES PATENT OFFICE.

JOHN KALIVODA, OF CUBA, KANSAS.

SCRAPER.

1,348,119.

Specification of Letters Patent. Patented July 27, 1920.

Application filed September 26, 1919. Serial No. 328,423.

To all whom it may concern:

Be it known that I, JOHN KALIVODA, a citizen of the United States of America, residing at Cuba, in the county of Republic 5 and State of Kansas, have invented new and useful Improvements in Scrapers, of which the following is a specification.

This invention relates to a scraper and has for its primary object the provision of 10 a scraper in which the scraping element may be quickly thrown to an operative or inoperative position by the driver changing his position upon the platform.

An object of the invention is the novel 15 manner of mounting and positioning the roller so that the scraper may be properly guided and the tendency of the latter to turn the scraper overcome.

Besides the above my invention is distinguished in the use of a roller arranged directly behind the scraper so that the ground may be rolled after the scraping operation and besides when found convenient the platform may be overbalanced for moving the 25 scraper out of engagement with the earth.

With these and other objects in view the invention will be better understood from the following detailed description taken in connection with the accompanying drawing, 30 wherein:—

Figure 1 is a top plan view of the scraper.

Fig. 2 is a side elevation.

Fig. 3 is a longitudinal sectional view.

Fig. 4 is a bottom plan view.

Again referring to the drawings illustrating one of the many forms in which the invention may be constructed, the numeral 1 designates a platform reinforced by the metal frame 2. This frame 2 has depending 35 bearings 3 and at the front has secured thereto hooks 4 by means of which the scraper may be drawn. At the front of the platform I arrange a scraper blade 5 extending at an angle to the direction of travel of the scraper when in use so as to convey and deposit the earth to one side of the road. By arranging the blade at an angle which is absolutely necessary in an apparatus of this character there is a tendency for the 45 scraper to move to one side of its line of travel owing to the angle of pressure between the scraper blade and the earth. To compensate for this action and besides to accomplish another beneficial effect I provide a roller 6. This roller 6 is of a length 50

approximately equal to the width of the platform and is arranged directly behind the scraper so that after the scraper has performed its function the roller will press the earth into a solid mass. The angular 60 position of the roller is such that it tends to move the scraper in a direction opposite to the action of the scraper blade and therefore the scraper is properly kept in its line of travel. The angular position of the roller 65 may be readily changed by adjusting the screws 7 that bind against the adjustable bearings 8 which are slidable within the bearings 3. To complete the invention I have formed an opening 9 in the top of the 70 platform so that access may be had to the roller for cleaning the same. By referring to Fig. 1 of the drawings it will be seen that the shaft 10 of the roller extends beyond the bearings so as to have attached thereto 75 wheels 11 in case the condition of the road makes it necessary to relieve the roller of a portion of the weight thereon.

From the foregoing description taken in connection with the accompanying drawing 80 it should be apparent that I provide an apparatus of simple substantial construction in which the parts are so related that the driver upon changing his position upon the platform may tilt the latter in a direction 85 to throw the blade out of engagement with the road.

It is of course to be understood that the invention may be constructed in various other manners and the parts associated in 90 other relation and therefore I do not desire to be limited in any manner except as set forth in the claims hereunto appended.

What I claim is:—

1. A road scraper comprising a platform, 95 elongated bearing members disposed upon the underside thereof at its edges, a laterally inclined blade carried at one end of the platform, bearing blocks slidably adjustable within said bearings, a roller having the 100 ends of its axle engaged within said blocks, and set screws extending into opposite sides of said first named bearing members and engaging said blocks whereby to vary the angular position of the roller. 105

2. A road scraper comprising a platform, an inclined scraper blade attached thereto at one end, a single roller extending at an angle transversely of the platform, and a device 110 for changing the angular position of the

roller with respect to the blade, whereby to counteract the tendency of the device to move laterally.

3. A road scraper comprising a platform, a scraper supported at an incline to the direction of travel of the scraper, a roller mounted under the platform with one of its bearings adjustable so that the angular position of the roller with relation to the blade 10 may be changed at will.

4. A road scraper comprising a platform, a scraper blade secured to the front edge of the platform at an angle to the direction of travel of the scraper, a roller of a length approximately equal to the width of the 15 platform and means for adjusting one of the bearings of the roller so that the angular position thereof may be changed at will.

In testimony whereof I affix my signature.
JOHN KALIVODA.
